UNITED STATES PATENT OFFICE.

WILLIAM E. AVRIL, OF SANTA MONICA, CALIFORNIA.

DESIGN FOR A MOTOR-VEHICLE BODY.

Application filed October 5, 1927. Serial No. 23,644 Term of patent 14 years.

To all whom it may concern:

Be it known that I, WILLIAM E. AVRIL, a citizen of the United States, residing at Santa Monica, in the county of Los Angeles, and State of California, have invented a new, original, and ornamental Design for Motor-Vehicle Body, of which the following is a specification, reference being had to the accompanying drawing, forming a part thereof.

Fig. 1 is a side elevational view of a motor vehicle body showing my new design.

Fig. 2 is a rear end view of a motor vehicle body embodying my new design.

I claim:

The ornamental design for a motor vehicle body, as shown.

WILLIAM E. AVRIL.
